UNITED STATES PATENT OFFICE.

FRANK SOLEY, OF PHILADELPHIA, PENNSYLVANIA, ASSIGNOR TO THE MILLER LOCK COMPANY, OF SAME PLACE.

PADLOCK.

SPECIFICATION forming part of Letters Patent No. 601,086, dated March 22, 1898.

Application filed October 4, 1897. Serial No. 653,945. (No model.)

To all whom it may concern:

Be it known that I, FRANK SOLEY, a citizen of the United States, residing in Philadelphia, Pennsylvania, have invented certain 5 Improvements in Padlocks, of which the following is a specification.

The object of my invention is to provide a padlock in which the shackle is locked either at the heel or at both the heel and nose, the 10 locking element or elements being immovably held in position when the lock is closed, so that the shackle cannot be freed by jarring or by blows upon the lock, the locking element or elements being, however, free from 15 this locking influence when the shackle is open and the closing of the shackle being effected with very slight effort.

In the accompanying drawings, Figure 1 is a view of a padlock constructed in accordance with my invention, the front portion of the casing and one of the retaining-washers being removed and the parts being shown in the closed position of the lock. Fig. 2 is a similar view showing the lock open. Fig. 3 20 is a vertical sectional view of the lock, looking toward the right-hand side of the same. Fig. 4 is a similar view looking toward the left-hand side of the lock, and Fig. 5 is a view illustrating a modification of the invention.

30 The casing 1 of the lock may be of any suitable size and dimensions and may be secured together in any available way, this forming no part of my invention.

In the lock shown in Figs. 1 to 4 the shackle 35 2 is hung to the pivot-pin 3, and has at its forward end a hooked nose 4 and at the pivot end a projecting heel 5 and a finger 6, the latter being recessed, or of less width than the heel 5, as shown in Fig. 2. To a pivot- 40 pin 7 are hung a pair of tumblers 9, having hooked upper ends for engaging with the hooked nose of the shackle, the depending portions of these tumblers being adapted to be acted upon by the bits of a key inserted 45 in the key-hub 10, which is adapted to bearings in the casing, so as to be free to turn therein in the usual manner. At the back of the lock is a lever 11, which is hung to a pivot-pin 12 on the back of the lock-casing, 50 this lever having a rearwardly and upwardly

projecting arm 13 and a downwardly and forwardly projecting arm 14, the latter having a projecting pin 15, and the inner side of said arm 14 being adapted to be acted upon by one of the bits of the key.

55

The tumblers are separated by the washer 16, and another washer 17 is interposed between the front tumbler and the front of the lock-case, as shown in Fig. 4.

Each of the tumblers 9 is acted upon by a 60 spring 19, which has a tendency to move the hooked upper end of the tumbler forwardly into engagement with the hooked nose of the shackle, and around a post 20 is coiled a spring 21, one arm of which acts upon the 65 arm 14 of the lever 11 to depress the same, while the other arm of said spring 21 acts upon the finger 6 of the shackle, so as to raise the same and cause the opening of said shackle.

70

When the lock is closed, the shackle is doubly locked, first, by engagement of the hooked ends of the tumblers 9 with the hooked nose of the shackle, and, secondly, by engagement of the rear arm 13 of the lever 11 with the 75 heel 5 of the shackle, and the tumblers 9 are also locked in the position shown in Fig. 1 by reason of the engagement of the lower arms of said tumblers with the projecting pin 15 on the arm 14 of the lever 11.

80

When the key is turned, one of its bits acts first upon the arm 14 of the lever 11, so as to raise said arm and its pin 15 and thus release the tumblers 9 from the locking influence of said pin, while at the same time the arm 13 of the lever is depressed, so as to free the heel 5 of the shackle, continued movement of the key serving to operate the tumblers 9 so as to withdraw their hooked upper ends from engagement with the hooked nose of the shackle, 85 and thereby permit the raising of said shackle by the action of the spring 21 upon the finger 6 of the same, as shown in Fig. 2. As the shackle is raised its heel 5 swings across the concave upper face of the arm 13 of the lever 90 11, which when the lever is in the raised position shown in Fig. 2 is substantially concentric with the path traversed by the end of said heel. Hence the lever 11 is retained in the raised position until the shackle has been 95 100

closed and its hooked nose engaged by the hooked upper ends of the tumblers, the heel 5 of the shackle finally leaving the concave upper face of the arm 13 of the lever 11 and permitting said arm to spring in behind the heel 5, so as to aid in locking the shackle. When the shackle is fully opened, the spring 21 acts but lightly upon it, but the pressure of the arm 13 of the lever 11 upon the heel 5 of the shackle serves to retain said shackle in the open position and prevents rattling or play of the same, while at the same time the shackle is free from any influence which would prevent the easy closing of the same by hand.

15 In the modified form of lock shown in Fig. 5 the shackle is locked solely by engagement of the arm 13 of the lever 11 with the heel 5 of the shackle, the tumbler 9^a being used simply to lock the lever 11 and having for this purpose a pin 15^a, which engages with a recessed portion of said lever 11 when the latter is in the locking position, the tumbler being swung outward by the key, so as to remove this pin from engagement with the lever and thus permit the latter to be in turn actuated by said key.

Having thus described my invention, I claim and desire to secure by Letters Patent—

30 1. The combination in a padlock, of the casing, a pivoted shackle having a projecting heel, a pivoted locking-lever adapted to be actuated by the key and having an arm for engaging with the heel of the shackle to hold said shackle in the closed position, one or more tumblers also adapted to be actuated by the key, and a single locking connection between said lever and tumblers whereby one locks the other only when the shackle is 35 closed, the tumblers being free and unadjusted when the shackle is open, and the heel-engaging arm of the locking-lever having a curved upper face which bears upon the heel of the shackle with a frictional braking effect 40 as said shackle swings open, whereby the locking-lever is held in the unlocking position during the opening of the shackle and

as long as the shackle is open, substantially as specified.

2. The combination in a padlock, of the casing, a pivoted shackle having a projecting heel and a hooked nose, one or more tumblers hooked for engagement with said hooked nose of the shackle and adapted to be actuated by a key, and a locking-lever also adapted to be actuated by the key, said locking-lever having one arm with projection so located in respect to the tumblers as to retain them in locking position only when the shackle is closed, and another arm with curved upper face which bears upon the heel of the shackle with a frictional braking effect as the shackle swings open, whereby the locking-lever is held in the raised position and the tumblers are free from its locking influence, during the opening of the shackle and as long as the same is held open, substantially as specified.

3. The combination in a padlock, of the casing, a pivoted shackle having a hooked nose and having also a heel and a finger projecting from the pivotal portion of the same, one or more tumblers adapted to be actuated by the key and having hooked ends for engaging the hooked nose of the shackle, a pivoted locking-lever having an arm with projection for engaging the tumbler or tumblers and holding the same in the locking position, and another arm which engages with the heel of the shackle and holds the latter in the closed position and is engaged by said heel of the shackle when the latter is open so as to hold the lever in the unlocked position, and a single spring, one end of which acts upon the finger of the shackle to open the same, the other end acting upon the locking-lever to depress the same, substantially as specified.

In testimony whereof I have signed my name to this specification in the presence of two subscribing witnesses.

FRANK SOLEY.
